UNITED STATES PATENT OFFICE.

JOHN NEIL, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,447, dated August 30, 1881.

Application filed July 29, 1881. Term of patent 3½ years.

To all whom it may concern:

Be it known that I, JOHN NEIL, of New York city, county and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The most prominent figures of this design are marked A and B on the photograph, and are placed one below the other, being separated by a diagonal stripe, I, which, at its lower portion, is bent at a right angle, so as to partly form the border for a hexagonal figure, D. At the junction of the figure D with the band I is the lower terminus of a curved stripe, q, which forms the lower outline of the figure A and reaches to another curved border, r, that extends up to a rectangular figure, r. This figure r forms the upper outline for the figure A, and when the carpet is matched reaches to the upper border, G, of the figure B, as indicated at the left-hand side of the photograph. The curved border j, having an angular portion, e, completes the outline for the figure A, excepting the small portion which, between the stripe j and the stripe I, is formed by a rectangular figure, J.

The outline for the figure B is formed by the border G, already referred to, the border I, and the hexagonal figure D, as shown at its upper part. At its right-hand side is an L-shaped border, m, which completes the outline at the right and at part of the bottom, and which abuts against a curved stripe, w. This in turn meets an angular figure, L, which completes the border or outline of the figure B, extending from the stripe w to the border G, as shown. The figures and borders already referred to complete nearly the entire design, leaving only room for two more hexagons, which are marked O and E in the photograph. The hexagon C abuts against the hexagon D, and is between D and E, as will clearly appear by comparing the portion of the hexagon C which is shown at the right-hand side of the photo-

graph, near the hexagon D, with the portions at the left-hand side of the photograph which are near the hexagon E there shown.

The several figures and the borders above described are ornamented in appropriate manner with flowers and geometrical designs. The main background of the figure A is chiefly ornamented by a fanciful floral group, (marked a, b, c, and s.) The part b of this group is a nearly-circular rosette located in part on the stripe g, and apparently forms the support for the larger circular rosette a, from which bursts forth the flower c with its manifold richly-decorated stems, buds, and conventional leaves. From the figure a project likewise flowers s, of which one extends to the border j, the other to the border q, as shown. There are other leaves most prominent at the junction of the circular figure a and b, which assist in completing the rich ornamentation of the figure A.

The figure B has on its background a decoration in many respects resembling that of the figure A. This ornamentation is shown at H in the drawing, and consists also of two circles, the smaller one supporting a larger one, from which bursts forth a prominent flower, that reaches across the curved border G nearly into the triangular figure d, that is formed between the figure r and the border G. Further, branches of flowers and buds extend from the figure H in all directions.

The hexagon D is ornamented by a narrow surrounding border, and within the same contains pyramidal groups, one above the other, as indicated. From this hexagon D project three prominent branches, p, into the adjoining hexagon C, and each of these branches bears within the hexagon C a rosette-like flower, t, there being thus three such rosettes within the figure C, the central one extending into contact with the figure E, and joining within the same with the ornamental rosette h, that is contained within the figure E. The space between the figures C and E and the stripe J contains a floral decoration, v, as shown. The stripe j, which partly surrounds the figure A, is double, having an outer border with vine-like ornamentation, and an inner border with small rosettes for its decoration. The figure r contains an ornamentation of cross-like figures

that are joined by diagonal stems, as shown. The stripe *g* has an inner geometrical pattern and an outer border, *i*, which is dotted and contains rosettes, as shown.

- 5 The figure L is decorated with an undulating border and with geometrical designs, mostly triangular, on straight stems within the undulations. The border I is also decorated with geometrical designs, as indicated, and 10 the border *q* has a series of rosettes set on a spotted or dotted background.

The border G of the figure B is made of two stripes, (marked, respectively, *f* and *y*.) The outer stripe, *f*, has triangular ornaments, the 15 inner, *y*, peculiar curvilinear ornaments resembling the claws of crabs set in line.

The figure J is decorated between its upper and lower borders with ornamentation of alternate small rosettes and larger H-shaped 20 figures. The figure J has a border, *x*, which separates it from the figure *r*. This border *x* is likewise most prominently decorated with geometrical designs. The stripe *m* contains 25 appropriate ornamentation, and the stripe *w*

has placed within it series of clover-like leaves, 25 which are joined by stems and tendrils.

I claim—

1. The design for carpets, consisting of the figures A, B, and I, substantially as shown.

2. The design for carpets, consisting of the 30 figure D, substantially as shown.

3. The design for carpets, consisting of the figure C, substantially as shown.

4. The design for carpets, consisting of the figure E, substantially as shown. 35

5. The design for carpets, consisting of the figures D, C, and E, substantially as shown.

6. The design for carpets, consisting of the figures *a*, *b*, *c*, and *s*, substantially as shown.

7. The design for carpets, consisting of the 40 figures B, H, and G, substantially as shown.

8. The design for carpets, consisting of the figures A, B, C, D, E, G, I, J, L, *a*, *b*, *c*, *s*, *g*, *i*, *q*, *j*, *e*, *h*, *t*, *p*, *x*, *f*, and *w*.

JOHN NEIL.
